UNITED STATES PATENT OFFICE.

HARRISON L. STALEY, OF MARTINSVILLE, INDIANA.

MOTION-AUGMENTING PENDULUM-GEARING.

1,153,268.

Specification of Letters Patent. Patented Sept. 14, 1915.

Application filed September 25, 1912. Serial No. 722,203.

To all whom it may concern:

Be it known that I, HARRISON L. STALEY, a citizen of the United States, residing at Martinsville, in the county of Morgan and State of Indiana, have invented a new and useful Improvement in Motion-Augmenting Pendulum-Gearing, of which the following is a specification, reference being had to the accompanying drawings and to the letters and figures of reference marked thereon.

This invention relates to the type of gearing that is designed to store energy imparted thereto and to give off the energy for augmenting the motion of other gearing, more especially lever actuated gearing, the invention having reference more particularly to a modification in construction of the motion augmenting pendulum gearing described in my pending application for Letters Patent of the United States, filed April 24, 1911, Serial No. 622,928.

An object of the present improvement is to provide motion augmenting gearing of the pendulum type that shall be so constructed as to be adapted for relatively high power and to be firmly supported, so as to permit relatively heavy swinging weight to be employed.

A further object is to provide relatively heavy and powerful motion augmenting pendulum gearing that shall be so constructed as to be adapted to be employed in connection with washing machines and without occupying appreciably greater space than required for the washing machine proper.

A still further object is to provide improvements in the construction of gearing of the above mentioned character to the end that the principal parts of the gearing, which may be subjected to the more severe swinging or oscillatory shocks, may be advantageously formed of tough bar metal and eliminate the more frangible cast metal.

A still further object is to provide pendulum gearing of the above mentioned character that shall be so constructed as to permit of relatively short suspension for the pendulum.

A specific object is to provide a compound pendulum and heavy and compactly arranged motion augmenting gearing thereon.

With the above mentioned and other objects in view, the improvement consists in a swinging compound pendulum of novel construction, in novel motion augmenting gearing mounted on the pendulum, in a novel

support for the pendulum, and novel means for actuating the motion augmenting gearing when the pendulum is actuated. The improvement comprises also certain novel parts and combinations and arrangements of parts as hereinafter particularly described and further pointed out in the appended claims.

Referring to the drawings, Figure 1 is a perspective view of a washing machine to which the improvement is applied; Fig. 2, a vertical sectional elevation centrally through the tub of the machine; Fig. 3, a fragmentary vertical section on the plane of the line A A in Fig. 2; Fig. 4, a fragmentary sectional plan view approximately on the line B B in Fig. 2; Fig. 5, a perspective view of one of the parts employed for connecting the motion augmenting gearing with a fixed support; Fig. 6, a fragmentary inverted sectional plan view approximately on the plane of the line C C in Fig. 3; Fig. 7, a fragmentary section approximately on the plane of the line D D in Fig. 3; Fig. 8, a fragmentary section approximately on the plane of the line E E in Fig. 3; Fig. 9, a fragmentary perspective view showing a portion of an improved balance wheel, and Fig. 10 is a perspective view of the principal portions of the improved pendulum and its support; the motion augmenting gearing being in substantially the same position in Figs. 6, 7 and 8, being different from that in the preceding figures.

Similar reference characters in the various figures of the drawings indicate corresponding elements or features of construction herein referred to.

The present improvement being particularly adaptable for washing machines, is illustrated in connection with a somewhat familiar type of washing machine which includes a tub comprising a side wall 1, a bottom 2, supporting legs 3, 4, 5, 6, a cover section 7 secured on the top of the side wall and a movable cover section 8 connected to the section 7 by means of hinges 9. The section 7 has a block 10 thereon, against which the section 8 leans when raised on its hinges to open position. A base plate 11 is secured upon the cover section 8 and has a journal-box 12 thereon that extends through the center of the section, the plate having also a pivotal stud 13 thereon. A rubber-actuating shaft 14 is rotatably mounted in the journal-box and extends into the tub to

be turned to and fro, a pinion 15 being secured to the upper end of the shaft, the lower end of the shaft having a collar 16 thereon. The shaft is provided with wings 5 17 extending upward from the collar. A rubber or agitator is employed and comprises a rubbing plate 18 mounted on the shaft so as to move up or down thereon and having slots 19 therein receiving the wings 10 so that the plate may be rotated by the shaft, the plate being provided with a suitable number of pins 20. An internal gear segment 21 is preferably employed and it has a hub 22 that is rotatably mounted on 15 the stud 13, the segment being provided with an ear 23 having a pivot 24 therein for operating and controlling the segment which is in mesh with the pinion 15. A stand 25 is mounted upon the cover section 8 and supports 20 a roller 26. A connecting rod composed of two bars 27 and 27' are connected at one end to the pivot 24 and extends at opposite sides of the roller, the opposite ends of the bars being secured to a filling block 28 25 provided with a pivot 29 to which a connecting rod part, comprising two bars 30 and 30' connected together by means of spacing studs 31, is connected at one end, the bars 30 and 30' extending beyond the cover part 7 30 and being preferably curved downwardly opposite the wall 1 of the tub. The connecting rod is knuckle jointed by means of the pivot 29 so as to permit the cover part 8 to be opened without disturbing the gearing connections, as illustrated in Fig. 1.

A suitable pivot block 32 is secured to the exterior of the wall 1 of the supporting tub. An operating lever of novel construction is provided which comprises two bars 33 and 40 34 spaced apart by means of tie rods 35, and they extend at opposite sides of the pivot block 32 and are connected therewith by means of a pivot pin 36, the upper portions of the bars being bent over each toward the 45 other to constitute handle portions 37 and 38 between which a wooden handle 39 is secured, the lever being connected to the bars 30 and 30' by means of a pivot pin 40. The bars of the lever have off-set portions 41 50 and 42 on their lower ends to which a foot bar 43 is connected so that the operator may assist with one foot in the operation of the lever.

In order to firmly support the motion augmenting apparatus a rail 44 is secured to the 55 lower portions of the legs 3 and 6 and a rail 45 is likewise secured to the legs 4 and 5, a substantial base 46 being secured to the two rails and supported thereby. Two 60 standards 47 and 48 are fixedly supported upon the base 46 at a suitable distance apart and preferably are afforded relatively broad base portions by means of supporting base 65 portions of two oppositely arranged journal boxes 49 and 50 secured also to the base 46

between the standards. A rocking guide bar 51 is provided which has two trunnions 52 and 53 on opposite ends thereof that are mounted in the journal boxes 49 and 50 respectively, the guide bar having a longitudinal slot or guideway 54 therein. The upper portions of the standards are provided with two pivots 55 and 56 respectively to which two pendulum arms 57 and 58 are respectively connected and swingingly supported. 75 The upper portion of the arm 57 has a head bar 59 thereon that extends toward the arm 58, the head bar having a supporting bar 60 thereon that extends downward between the two arms 57 and 58. A foot bar 61 is integrally connected to the lower ends of the arm 58 and the bar 60. A separate foot bar extension 62 is secured to the bar 61 and extends to the arm 57 and has a journal-box 63 arranged between the arm 57 and the bar 60. 80 The extension has an ear 64 which is secured to the arm 57, and the lower end portion of the arm 57 and the ear 64 have a pivot 65 connected therewith. The under side of the extension 62 has a boss 66 and a 85 suitable aperture that registers with an aperture 67 formed in the middle portion of the bar 61. The head bar 59 has an aperture 68 therein in alignment with the journal-box 63. A stud axle 69 is secured to the 90 boss 66 and has a head 70 on its lower end supporting a gear wheel 71 that is rotatably mounted on the axle 69. The wheel 71 has spur teeth and it is provided with a crank pin 72 that projects downwardly at a suitable distance from the axis of the wheel and into the slot or guideway 54 of the guide bar, the crank pin preferably having a roller 73 thereon that is fitted closely into the slot so as to cause the guide bar to rock when the pendulum swings the gear wheel 71, the crank pin being carried along the slot when the gear wheel rotates. When at 100 rest the pendulum, owing to the weight of its component parts including the gearwheel 71, and through the force of gravity, hangs in mid position so that the crank pin is in either end portion of the slot in the guide bar while the axis of the wheel 71 is approximately in alignment transversely with the slot. A suitable ball casing 74 having bearing balls 75 therein, of well known construction, is seated upon the head bar 59 and a shaft 76 is inserted through the casing and also through the aperture 68 and the journal box 63 and is supported by means of a hub 77 of a combination pendulum weight and balance wheel, the under side of the hub having a recess 78 therein that receives a pin 79 driven through the shaft, the pin being normally secured in the recess by a nut or other device on the upper end of the shaft, the hub being seated upon the ball casing 74. The wheel hub 77 has oblique angled spokes 80 thereon that extend ra- 105 110 115 120 125 130

dially and downwardly beyond the axis of the pivots 55 and 56 toward the foot bar 61 of the pendulum, the balance wheel comprising also a relatively heavy rim 81 connected to the ends of the spokes, it being obvious, however, that the wheel may have a dished web in lieu of the spokes. A spur-toothed pinion 82 is secured to the lower end of the shaft 76 in mesh with the gear wheel 71 and therefore the balance-wheel must rotate when the pendulum swings and the gear wheel 71 rotates, the balance-wheel also swinging with the pendulum.

In order to derive the benefit of the motion augmenting gearing a suitable connecting rod is provided which preferably comprises two bars 83 and 84 spread apart between the bars 83 and 84 of the lever and connected thereto by a pivot rod 85, the bars 83 and 84 being bent so as to extend downwardly from the pivot rod to clear the balance-wheel and thence under it to the pivot 65 whereby they are connected with the lower end of the pendulum, the bars 83 and 25 84 being connected together by tie rods 86, the lower portion of the bar 84 extending over nearly to the bar 83.

In practical use, the tub having been properly charged and the cover section 8 closed, 30 the handle 39 is moved by the operator forward and backward and reciprocating movement is thus imparted to the knuckled connecting rod which operates the gear segment 21 and its connections, for moving the rubbing plate 18 on the articles to be washed. The moving lever causes the pendulum to swing so that the gear wheel 71 rotates and drives the balance-wheel at high speed, the 35 balance-wheel when set in motion being enabled to assist in reversing the motion of the operating lever, and also gives out the energy stored therein to operate the lever and all the gearing for a time after the actuating force on the lever is discontinued.

Having thus described the invention, what is claimed as new is:—

1. Gearing including a pendulum swingingly supported, a slotted guide bar, a wheel 50 rotatably mounted on the pendulum, and means coöperating with the slotted guide bar for rotating the wheel on movement of the pendulum.

2. Gearing including a pendulum swingingly supported, a wheel rotatably mounted 55 on the pendulum and having a crank pin thereon, and means connected with the crank pin for rotating the wheel on movement of the pendulum.

3. Gearing including a rocking guide bar, a pendulum device supported to swing over the guide bar, and a wheel rotatably mounted on the device and provided with a crank pin having sliding and also rotative connection 60 with the guide bar.

4. Gearing including a pivoted lever, a

pendulum device swingingly suspended, a rod connected to the lever and also to the pendulum device, a wheel rotatably mounted on the device, and means for rotating the wheel on swinging movement of the pendulum device.

5. Gearing including a longitudinally slotted guide bar supported to rock on its longitudinal axis, a pendulum device supported to swing over the guide bar, and a 70 wheel rotatably mounted on the device and provided with a crank pin that extends into the slot of the guide bar.

6. Gearing including a support having legs, a lever pivotally connected to the support, a pendulum swingingly supported between the legs under the support, a rod pivotally connected to the lever and also to the pendulum, and motion-augmenting apparatus movably mounted on the pendulum.

7. Gearing including a pendulum swingingly supported, a lever pivotally supported at a distance from the pendulum, a rod pivotally connected to the lever and the pendulum, a wheel rotatably mounted on the 90 pendulum, and means for rotating the wheel on movement of the pendulum.

8. Gearing including a swingingly supported pendulum, a shaft and also a gear wheel rotatably mounted on the pendulum, a 95 pinion secured to the shaft in mesh with the gear wheel, a balance-wheel secured to the shaft, and means for rotating the gear wheel on swinging movement of the pendulum.

9. Gearing including a rocking guide bar, 100 a pendulum swingingly supported, a balance-wheel rotatably mounted on the pendulum, a lever for swinging the pendulum, and means coöperating with the rocking guide bar for rotating the balance wheel on 105 movement of the pendulum.

10. Gearing including a supported standard, a pendulum arm pivoted to the standard, a shaft rotatably mounted on the arm, a balance-wheel secured to the shaft and 110 having a rim that extends about the standard and the arm, and means for rotating the shaft on movement of the arm.

11. Gearing including a pendulum swingingly supported, a balance-wheel rotatably 115 supported on the pendulum, speed increasing gearing mounted on the pendulum below the plane of the balance-wheel and operatively connected with the latter, and means for rotating the speed-increasing gearing on 120 swinging movement of the pendulum.

12. Gearing including a fixed base, a guide bar mounted on the base, a pendulum pivotally supported to swing above the base, a balance-wheel rotatably mounted on the pendulum, and means movably mounted on the pendulum and coöperating with the guide bar for rotating the balance wheel on movement of the pendulum.

13. Gearing including a pendulum swing-

ingly suspended, a shaft rotatably mounted on the pendulum, a balance-wheel and a pinion secured to the shaft, a gear wheel rotatably mounted on the pendulum in connection with the pinion and having a crank pin thereon, and means connected with the crank pin for rotating the gear wheel on movement of the pendulum.

14. Gearing including a pendulum device 10 swingingly supported and having a weight element rotatably mounted thereon, a lever pivotally supported in a plane higher than the support of the pendulum device, a rod pivotally connected to the lever and the 15 pendulum device below their supports, and means for rotating the weight element on movement of the pendulum device.

15. Gearing including a pendulum having 20 two arms pivotally suspended, a shaft rotatably mounted on the pendulum adjacent to one of the two arms, a balance-wheel and a pinion secured to the shaft, a gear wheel rotatably mounted on the pendulum and connected with the pinion, means for 25 swinging the pendulum, and means for rotating the gear wheel on movement of the pendulum.

16. Gearing including a rocking guide bar, a pendulum pivotally supported to swing 30 transversely over the bar, a gear wheel rotatably mounted on the pendulum and provided with a crank pin having sliding and also rotative connection with the guide bar, a balance-wheel rotatably mounted on the pendulum, and means enabling the gear wheel to rotate the balance-wheel.

17. Gearing including a horizontally supported base, two standards mounted uprightly upon the base, a pendulum having 40 two arms pivotally connected to the two standards respectively, a balance-wheel rotatably supported on the pendulum, a pivoted lever, a rod pivotally connected to the lever and the pendulum, and means coöperating with the base and the pendulum for 45 rotating the balance-wheel on movement of the lever.

18. Gearing including a pendulum having two arms pivotally suspended, a gear wheel 50 rotatably mounted on the pendulum and having a crank pin thereon, a balance-wheel rotatably mounted on the pendulum and operatively connected with the gear wheel, a pivoted lever, a rod pivotally connected to the lever and also to one of the two arms of the pendulum, and means connected with the crank pin rotating the gear wheel on movement of the pendulum.

19. Gearing including a lever and a pendulum separately supported to swing pivotally, means connecting the lever and the pendulum together to swing simultaneously, motion-augmenting apparatus movably mounted on the pendulum, a fixed base, and 60 means mounted on the base enabling the ap-

paratus to acquire momentum on movement of the pendulum by the lever for transmitting the momentum to the lever succeeding reversing of direction of motion of the lever.

20. Gearing including a support, a lever 70 pivoted to the support, a gearing mounted on the support and operatively connected with the lever, a pendulum device pivotally hung under the support, a balance-wheel rotatably mounted on the pendulum device, 75 gearing acting on movement of the pendulum device to rotate the balance-wheel, and a rod pivotally connected to the lever and the pendulum device.

21. In washing machine gearing, the combination with a base, two journal boxes mounted on the base, and a pendulum pivotally supported to swing above the base, of a guide bar having two trunnions rotatably mounted in the journal boxes and having a 80 slot therein extending longitudinally between the two trunnions, and a gear wheel 85 rotatably mounted on the pendulum and having a crank pin thereon extending movably into the slot of the guide bar. 90

22. In washing machine gearing, the combination with a stationary support, a lever pivotally mounted on the support, and gearing mounted on the support and operatively connected with the lever, of a pendulum 95 swingingly mounted under the support, a rod connected to the lever and also to the pendulum, a balance-wheel rotatably mounted on the pendulum, speed-increasing gearing mounted on and carried by said pendulum and operatively connected with said balance-wheel, and means for operating the speed-increasing gearing on movement of said pendulum. 100

23. In washing machine gearing, the combination with a stationary support, a lever pivotally mounted on the support, and a base fixedly secured below the support, of a pendulum swingingly mounted upon the base and under the support, a balance-wheel 105 rotatably mounted on said pendulum, a rod connected to the lever and also to the pendulum, speed-increasing gearing mounted on and carried by said pendulum and operatively connected with said balance-wheel, 110 and means coöperating with said base for rotating said gearing on movement of said pendulum. 115

24. In washing machine gearing, the combination with a base, of two standards fixedly 120 mounted uprightly on the base, and a pendulum comprising two arms of different length pivotally connected to the two standards respectively, a head bar extending from the longer one toward the opposite one of the two arms, a hanger bar extending downward from the head bar between the two arms, a foot bar extending from the lower end of the hanger bar to the lower end of said opposite one of the two arms, and an extension se- 125 130

cured to the foot bar and having an ear secured to the longer one of the two arms.

25. In washing machine gearing, the combination with a support, an operating lever pivoted to the support, and a shaft rotatably supported, of a guide supported for movement relatively to the support, a pinion on the shaft, an internal gear segment pivotally supported adjacent to the shaft and in connection with the pinion, and a knuckle-jointed connecting-rod having one part pivotally connected to the gear segment and guided by said guide, the remaining part of the connecting-rod being pivotally connected to the operating-lever.

26. In washing machine gearing, the combination with a support, a lever pivotally mounted on the side of the support, and a base fixedly secured below the support, of two standards secured uprightly upon the base, a pendulum having two arms pivotally connected to the standards, a shaft rotatably mounted on the pendulum, a balance-wheel secured to the upper portion of the shaft, a pinion secured to the lower portion of the shaft, a rod pivotally connected to the lever and extending downwardly and under the balance-wheel and pivotally connected to the pendulum, a gear wheel rotatably mounted on the pendulum in mesh with said pinion, and means for rotating the gear wheel on movement of the pendulum.

27. In washing machine gearing, the combination with a support, a pivot-block secured to the side of the support, a base fixedly secured below the support, of a lever comprising two bars pivotally connected to the pivot-block, a pendulum swingingly supported upon the base, a connecting-rod comprising two bars pivotally connected to the pendulum and also to said lever, a foot-bar connected to the lower portions of the two bars of the lever, a balance-wheel rotatably mounted on said pendulum, speed-increasing gearing mounted on the pendulum and operatively connected with the balance-wheel, and means coöperating with said base for actuating the said gearing on movement of said pendulum.

28. In washing machine gearing, the combination of a pendulum device, a support extending under and also above the pendulum device and provided with pivoting means swingingly supporting the pendulum device, actuating means mounted on the support above the axis of rotation of the pivoting means, means operatively connecting the pendulum device with the actuating means for enabling the actuating means to swing the pendulum device, and a balance-wheel rotatably mounted on the pendulum device and provided with means for rotating the balance-wheel.

29. In washing machine gearing, the combination of a pendulum having two arms

swingingly supported, a balance-wheel rotatably mounted on the pendulum and having a rim extending about one of the arms, a crank device rotatably mounted on the pendulum and having a crank pin thereon, means operatively connecting the balance-wheel with the crank device, and means connected with the crank pin for rotating the crank device on swinging movement of the pendulum.

30. In washing machine gearing, the combination of a supporting structure, a pendulum device swingingly supported under the structure and including speed-increasing apparatus and a rotatable balance-wheel connected with the apparatus, and actuating means having support on the structure and operatively connected with the pendulum device.

31. In washing machine gearing, the combination of a supporting structure, a lever pivotally supported on one side of the structure, and motion-augmenting pendulum gearing including rotatable and swinging means movably supported under the structure and operatively connected with the lever.

32. In washing machine gearing, the combination of a pendulum device swingingly supported, a shaft rotatably mounted on the device in vertical arrangement, a balance-wheel fixedly secured to the shaft, and an actuating device rotatably mounted on the pendulum device below the wheel and having operative connection with the shaft below the wheel for rotating the shaft.

33. In washing machine gearing, the combination of a pendulum device, a pivot supporting the device, a shaft rotatably mounted on the device in vertical arrangement and extending below the axis of the pivot, a balance-wheel secured to the shaft, and an actuating device fixed on the shaft below the axis of the pivot for rotating the shaft.

34. In washing machine gearing, the combination of a supported guide bar, a pendulum device supported to swing above the guide bar, a wheel rotatably mounted on the pendulum device, and connecting means having movable actuating contact with the guide bar for rotating the wheel on swinging movement of the pendulum device.

35. In washing machine gearing, the combination of a pendulum device swingingly supported, a supported guide, a combination weight and balance-wheel rotatably mounted on the device, and connecting means co-operating with the guide for rotating the combination weight and balance-wheel on swinging movement of the device.

36. In washing machine gearing, the combination of a pendulum device, a pivot supporting the device, a shaft rotatably mounted on the device in vertical arrangement and extending above the axis of the pivot, and

a balance-wheel secured to the shaft above and extending below the axis of the pivot.

37. In gearing, a pendulum device swingingly supported and having a shaft and also a gear wheel rotatably supported thereon, the gear wheel having a crank pin, a pinion fixed on the shaft and meshing with the gear wheel, a balance wheel fixedly secured to the shaft, and means coöperating with the crank

pin for rotating the gear wheel on swing-¹ ing movement of the pendulum device.

In testimony whereof, I affix my signature in presence of two witnesses.

HARRISON L. STALEY.
